(Cl. D26—13)

Fig. 1.

Fig. 2.

Fig. 3.

Fig. 4

FIG. 1 is a top plan view of a tuning knob for a television receiver or similar article, showing my new design;

FIG. 2 is a side elevational view, the opposite side being substantially a mirror image thereof;

FIG. 3 is a side elevational view partly in cross-section, taken on line 3—3 in FIG. 1; and

FIG. 4 is an enlarged, exploded perspective view thereof.

The essential features of my new design are shown in solid lines in the drawing.

I claim:

The ornamental design for a tuning knob for a television receiver or similar article, as shown and described.
